(57) **CLAIM**

The ornamental design for a vehicle rear quarter louvered window, as shown and described.

DESCRIPTION

FIG. 1 is a first perspective view of a vehicle rear quarter louvered window;

FIG. 2 is a second perspective view of a vehicle rear quarter louvered window; and,

FIG. 3 is a third perspective view of a vehicle rear quarter louvered window.

In the drawings, the broken lines in the figures depict portions of the article that form no part of the claimed design.
